UNITED STATES PATENT OFFICE.

JOSEPH L. FIRM, OF BERWYN, ILLINOIS, ASSIGNOR TO THE GOSS PRINTING PRESS COMPANY, OF CHICAGO, ILLINOIS.

PRINTING-MACHINE.

971,533.

Specification of Letters Patent.

Patented Oct. 4, 1910.

Application filed February 5, 1910. Serial No. 542,343.

To all whom it may concern:

Be it known that I, JOSEPH L. FIRM, a citizen of the United States, residing at Berwyn, in the county of Cook and State of Illinois, have invented certain new and useful Improvements in Printing-Machines, of which the following is a specification.

The object of my invention is to produce a web printing-press which will produce 10 plicated magazines or pamphlets, stapled, cut and folded, in separate signatures, at one operation. To produce a machine of this kind I use one form and one impression cylinder to each deck; at the same time I 15 use a half width web—that is, a web half the width of the entire length of the cylinders—and reverse the web and shift it to the opposite side of the cylinders, so that the first passage of the web prints one side 20 thereof by contact with the half of the cylinder at one end, and the other side of the web is printed by contact with the half of the cylinder at the other end, in its second passage; thence slitting, turning and folding 25 the web longitudinally, thence cutting, stapling and folding the slit webs transversely, thence delivering the products to a moving apron.

In the drawings of my printing-press, as 30 I prefer to embody it, Figure 1 is a diagrammatic side elevation. Fig. 2 is an end elevation, the paper rolls being removed. Fig. 3 is a diagrammatic side elevation of a modification.

The press as shown consists of two printing mechanisms A and B, printing, respectively, on rolls C, D and E and F. These two sets of printing mechanisms A and B, as is shown in Fig. 1, are arranged in decks, 40 one on top of the other, an upper deck consisting of one form and one impression cylinder, and a lower deck of one form and one impression cylinder, with their appropriate inking devices together with folding 45 and stapling mechanism at the middle. I do not wish to confine myself to this particular construction, for they may have one or more decks added, or may have decks side by side, or decks facing each other.

50 It is obvious that variations are possible as to the number of plates placed on the form cylinders, this being governed by the size of one of the plate cylinders and the

diameter of the same. The column rules of the plates may be at right angle or parallel 55 to the axis of these cylinders. In the present case I use on each form cylinder four double plates around and four pages wide making 32 pages on each half of the form cylinder, with column rules parallel to the axis of the 60 form cylinder, each plate having two pages thereon, making magazines or pamphlets of 16 or 32 pages, from each deck, slit, cut, stapled and folded.

It is understood that by adding webs from 65 each of the other decks the size of the products is enlarged, as to the number of pages, and the pamphlets increased, as the four decks are alike in their essential characteristics, and a description of one deck in detail 70 will be sufficient for all of them.

In Fig. 1, C is a roll or web of paper passing over the rollers 1—2, to impression cylinder 3, and is printed upon one side by one half of form cylinder 4, thence around 75 the roller 5, thence over the turing bars 6, under the roller 7, back to impression cylinder 3, and is printed on its reverse side on the other half of form cylinder 4, thence under the roller 8, and is slit by the slitter 9, 80 thence over the bars 10—11 and between the rollers 12, 13, 14, where it meets the web D. This web D passes over the rollers 15, 16, thence to impression cylinder 17, and is 85 printed upon by one half of form cylinder 18, on one side, thence over the roller 19, to the turning bars 20 and under the roller 21, thence to impression cylinder 17, and is printed upon its reverse side by the other half of form cylinder 18, thence passes under the roller 20^a, and slit by the slitter 21^a, 90 thence over the turning bars 22—23 and under the roller 24, where it meets the web C, passing between the rollers 12, 13, 14, thence between the rollers 25, 26, where it meets the webs E and F. The web E passes over the rollers 27, 28, to impression cylinder 29, and is 95 printed on one side by form cylinder 30, thence passes over the roller 31, to the turning bars 32, thence under the roller 33, to impression cylinder 29, and is printed on the reverse side by the other half of form cylinder 30, thence under the roller 34, over the turning bars 35, 36, and between the rollers 37, 38, where it meets the web F. 100 This web F passes over the rollers 39, 40, 105

and is printed on its first side by half of impression cylinder 41, on form cylinder 42, thence passes under the roller 43, and over the turning bars 44, 45, thence under the 5 roller 46, and over impression cylinder 41, and is printed on its reverse side by the other half of form cylinder 42, thence under the roller 47, and is slit by slitter 48, thence over the bars 49, 50, thence under the roller 51, 10 thence between the rollers 37, 38, 39, where it meets the web E, and is associated with the webs C and D between the rollers 25, 26 where all the webs are slit by the slitters 200 and 201, and thence pass to the stapling 15 mechanism S (of known construction) for a finished product.

As a modification the longitudinal folders 100, 101, which are shown in Fig. 3, if preferred could be used by passing the webs 20 thereover as indicated at 102 and 103 and placing the stapling mechanism at right angles and leading the longitudinally folded webs thereto.

It is to be understood that an off-set web 25 can be used if desired in the same manner as shown in Fig. 1, of U. S. patent to me No. 677737, July 2, 1901. Also as to the manner

of turning the web over bars to reverse it for its second printing, see Fig. 7, of same patent.

What I claim as new is:—

In a multiple web printing machine, the combination of two sets of web-perfected printing mechanisms arranged end to end, each set including a plurality of decks 35 spaced from each other and each deck including cylinder printing couples, means to feed webs from rolls into opposite ends of the machine, for the respective decks, means to pass the webs twice through said couple, once at each end, including turning devices located in the spaces between the decks, a stapling, transverse cutting and folding mechanism between the adjacent ends of said sets, and means to associate and deliver the webs from the respective sets to said stapling, transverse-cutting and folding mechanism.

In testimony whereof I affix my signature in presence of two witnesses.

JOSEPH L. FIRM.
